UNITED STATES PATENT OFFICE.

RAYMOND H. SULLIVAN, OF ROCHESTER, NEW YORK, ASSIGNOR TO NORTH EAST ELECTRIC COMPANY, OF ROCHESTER, NEW YORK, A CORPORATION OF NEW YORK.

VIBRATORY REGULATOR.

Application filed April 17, 1922. Serial No. 553,910.

To all whom it may concern:

Be it known that I, RAYMOND H. SULLIVAN, a citizen of the United States, residing at Rochester, in the county of Monroe and 5 State of New York, have invented certain new and useful Improvements in Vibratory Regulators; and I do hereby declare the following to be a full, clear, and exact description of the invention, such as will enable 10 others skilled in the art to which it appertains to make and use the same.

This invention relates to regulators, such as are commonly used in connection with electric generators, of the type wherein the 15 current flowing through a field-winding of the generator is varied by means of a pair of contacts which are engaged and disengaged by a rapid vibratory movement.

Regulators of the type in question, which 20 may be designated broadly as "vibratory regulators," are necessarily provided with contacts consisting of material sufficiently refractory to withstand the arcing and heating resulting from the frequent interruption of 25 the field-current. The movement of the contacts is generally produced or controlled by an electromagnet energized by the generated current, and arranged to be controlled in accordance with either the intensity, or the 30 voltage of the current, or by some function of the two.

In regulators of this type difficulty is encountered both through the burning and sticking of the contacts, and through changes 35 in the resistance of the magnet-winding due to heat communicated to the winding from the contacts. To diminish the first difficulty it has been proposed to use carbon as the material of the contacts, but this tends to 40 accentuate the second trouble, since more heat is generated in carbon contacts than in contacts of metal.

The object of the present invention is broadly, to improve regulators of the type 45 in question in such a manner as to increase the useful life of the contacts and to make the regulating action more uniform and reliable. To this end I propose to use contacts consisting wholly or chiefly of carbon or of 50 other refractory material of similar characteristics, and to mount the contacts in such a way as to confine in the contacts themselves the heat generated therein. In the best embodiment of my invention the contacts are 55 shunted by a resistance-device, and I have

found that a device having a high positive temperature coefficient of resistance is peculiarly suited for this purpose. With such a combination of parts a regulator may be produced in which the contacts have an unusually long life, while the action of the regulator is remarkably constant under the most adverse circumstances. I have further discovered that by the use of heat-insulating means associated with the carbon contacts, 60 the total amount of heat generated in the contacts is reduced, owing, apparently to the reduction in the resistance of the contacts due to their negative temperature coefficient 65 of resistance.

In the accompanying drawings Fig. 1 is a side-elevation, partly in section, of a regulator embodying the present invention. Fig. 2 is a plan-view of the same regulator without its casing and mounting; and Fig. 3 is 70 a diagram showing the preferred circuit connections of the regulator when used to control the voltage of a generator.

The invention is illustrated as embodied in a vibratory electromagnetic regulator 80 comprising a magnet-core 5 and a U-shaped yoke or heel-iron 7. To one arm of the latter the iron armature 6 is pivoted, and the movement of the armature is controlled by a spring 8. The tension of the spring may 85 be adjusted by a screw 9.

The contacts 10 and 11 controlled by the armature are in the form of carbon blocks. The contact 11 is attached to the armature by a strip 12 of German silver or of some 90 other material having low heat-conductivity. In the illustrated device the strip 12 also acts as an electrical connection for the carbon, and for this reason it should be of generous cross-section, as the metals having low heat-conductivity, of the order of that of German 95 silver, have also low electric conductivity.

The contact 10 is mounted on a strip 13 of German silver, and this strip is fixed to one arm of the heel-iron by screws 14, but 100 insulated from the heel-iron. The strip 13 is thick enough to be rigid, but it may be bent to adjust the contact 10 for accurate engagement with the other contact. The lower end of the strip 13 is attached directly to a binding-post 15, fixed in the insulating base 16 105 of the regulator.

The magnetic vibrator or relay just described is entirely enclosed, for protection 110 against dust and moisture, in a casing com-

prising a body 17 and a removable cover 18. The cover is secured in place by a bolt 19. Owing to this enclosure of the regulator the heat generated in the windings and the contacts is confined, so that the temperature of the windings tends to become high during continued use. To compensate for this the illustrated regulator is provided with a compensating device of the kind disclosed in U. S. Patent No. 1,398,463 to Thomas L. Lee.

This device consists of a block 20 of Monel metal which, owing to its negative temperature coefficient of magnetic permeability, acts as a magnetic shunt of varying effectiveness, and thus compensates for the changes in the resistance of the windings.

The Monel-metal shunt, while effective through a certain range of temperatures, ceases to be effective at a temperature somewhat above 212° Fahrenheit. In this respect the use of the German silver supports for the contacts is important, since it so far prevents the transmission of heat from the contacts, as to keep the temperature of the other parts of the instrument within the range at which the compensating-device is effective.

To prevent radiation of heat from the contacts to the magnet, a shield 21 of non-conductive material may be interposed between the magnet and the contacts, as shown in Fig. 1.

The tungsten lamp 22 which is preferably used as a shunt resistance device, is enclosed in a casing 23 entirely distinct from that of the vibratory relay, so that heat from the lamp cannot affect the magnet. The two casings are mounted on a common base or panel-member 24, which may be attached to a vertical surface, such as that of the dash-board of a motor-vehicle.

The electrical connections of the apparatus are shown in Fig. 3. The generator 25 which is to be regulated has two main brushes 26 and 27, and a third or auxiliary brush 28 through which the shunt field-winding 29 is energized. The main brushes are connected, through main conductors 30 and 31, with a storage-battery or other load (not shown). The relay is shown as arranged to maintain substantially uniform voltage in the main conductors, being provided with a high-resistance winding 32 connected across the main conductors through wires 33 and 34. The armature is connected by a wire 35 with the wire 33, and the contact 10 is connected, through a wire 36, with the field-winding. The circuit of the field-winding is thus normally completed, to the main brush 26, through the wires 36, 35, 33 and 30 and the contacts 10, 11 of the regulator. Whenever the voltage rises above the predetermined amount the contacts separate momentarily, thus introducing resistance into the circuit of the

field-winding. The current is thus partially diverted through the lamp 22, which is connected in series with the field-winding by means of a wire 38.

To insure steady vibratory action of the regulator, it is provided with a second winding 37 which is connected in shunt with the contacts and in opposition with the winding 32. This winding 37 acts, in a well known manner, to limit the amplitude of the movement of the armature 6.

While a tungsten lamp has been found particularly effective as a resistance-device in connection with a relay having the particular characteristics of that herein described, the use of the lamp, or of any resistance-device, is not essential to the invention in its broader aspects, and the invention is not limited in general, to the details of the embodiment herein described.

The invention claimed is:

1. A vibratory regulator, having contacts of which at least one consists of material with a negative temperature coefficient of resistance, and a support, for such contact, consisting of material of low heat-conductivity whereby rise in the temperature of the contact during operation is promoted.

2. In a vibratory regulator, the combination of a carbon contact, and a support therefor consisting of metal having a low heat-conductivity of the order of that of German silver.

3. In a vibratory regulator, the combination, with actuating means comprising an electromagnet and its armature, of contacts controlled thereby of which at least one consists of carbon; and a support, for said contact, mounted on an element of said actuating means and consisting of material of low heat-conductivity.

4. In a vibratory regulator, the combination, with an electromagnet and its armature, of carbon contacts controlled thereby; and supports, for said contacts, mounted on the magnet and the armature and consisting of electrically conductive material of low heat-conductivity.

5. In a vibratory regulator, the combination, with a magnet and its armature, and contacts controlled thereby, of a casing enclosing the magnet, the armature and the contacts; and means for shielding the magnet from heat generated in the contacts.

6. In a vibratory regulator, the combination, with a magnet and its armature, of carbon contacts controlled thereby; a casing enclosing the magnet, the armature and the contacts; and means for restricting the heat generated in the contacts to the vicinity of the contacts.

7. In a vibratory regulator, the combination, with a magnet and its armature, of carbon contacts controlled thereby; a casing enclosing the magnet, the armature and the

contacts; means for restricting conduction of heat from the contacts; and a resistance-device shunting the contacts but located outside said casing.

5. 8. In a vibratory regulator, the combination, with a magnet and its armature, of carbon contacts controlled thereby; heat-

insulating supports for the contacts; a casing enclosing the magnet, the armature and the contacts; and a resistance-device, with a high temperature coefficient of resistance, shunting the contacts and located outside the casing.

RAYMOND H. SULLIVAN.
